United States Patent Office

Des. 212,046

Patented Aug. 20, 1968

212,046

RADIO

David B. Rote, Fort Wayne, Ind., assignor to Arvin Industries, Inc., Columbus, Ind., a corporation of Indiana

Filed Nov. 6, 1967, Ser. No. 9,294

Term of patent 14 years

(Cl. D56—4)

Fig. 1

Fig. 2

Fig. 3

FIG. 1 is a perspective view of a radio showing my new design;

FIG. 2 is an end elevation thereof; and

FIG. 3 is a rear elevation thereof.

The dominant features of the design are shown in full lines.

I claim:

The ornamental design for a radio, as shown and described.
